UNITED STATES PATENT OFFICE.

AUGIE L. HANSEN, OF EVANSTON, ILLINOIS, ASSIGNOR TO CHICAGO TITLE & TRUST CO., TRUSTEE, A CORPORATION OF ILLINOIS.

DESIGN FOR A BODY FOR A MASSAGE DEVICE.

47,952.

Specification for Design.

Patented Oct. 12, 1915.

Application filed March 7, 1912. Serial No. 632,265. Term of patent 14 years.

To all whom it may concern:

Be it known that I, AUGIE L. HANSEN, citizen of the United States, residing at Evanston, in the county of Cook and State of Illinois, have invented a new, original, and ornamental Design for a Body for a Massage Device, of which the following is a specification, reference being had to the accompanying drawing, forming a part hereof.

The invention has for its object to provide a novel and ornamental design for a body for a massage device.

In the accompanying drawings illustrating the design: Figure —1— is a perspective view of a massage device embodying my design. Fig. —2— is an end elevation of the device.

I claim:

The ornamental design for a body for a massage device as shown.

AUGIE L. HANSEN.
